Patented May 12, 1914.

UNITED STATES PATENT OFFICE.

CLIFFORD L. DUNBAR, OF DETROIT, MICHIGAN.

SHEET-METAL STRUCTURAL ELEMENT.

1,096,612.

Specification of Letters Patent.

Patented May 12, 1914.

Application filed December 17, 1912. Serial No. 737,159.

To all whom it may concern:

Be it known that I, CLIFFORD L. DUNBAR, a citizen of the United States of America, residing at Detroit, in the county of Wayne 5 and State of Michigan, have invented certain new and useful Improvements in Sheet-Metal Structural Elements, of which the following is a specification, reference being had therein to the accompanying drawings.

10 The invention relates to structural elements, and it is the particular object of the invention to obtain a construction of sheet metal beam in which the adjacent portions are connected and braced by one or more 15 sections struck out from adjacent to the neutral axis of one or both portions of the member.

The invention consists in the peculiar construction of this bracing member; further 20 in the construction of the beam or other structural member of a folded blank; and further in various features of construction as hereinafter set forth.

In the drawings: Figure 1 is a plan view 25 of the blank from which the beam is formed. Fig. 2 is a perspective view, partly in section, of a portion of the completed beam. Fig. 3 is a cross section on line $x-x$ Fig. 4. Fig. 4 is a central longitudinal section on 30 line $y-y$ Fig. 3. Fig. 5 is a perspective view of a modified construction.

My improved beam or structural member comprises essentially a sheet metal member having a portion struck out from adjacent 35 to the plane of the neutral axis and folded to form a connecting brace with an adjacent member. A simple form is illustrated in Fig. 5, in which a sheet metal blank is bent to form an angle bar having the adjacent 40 flanges A and B. From the flange A a section C is struck out from the portion adjacent to the plane of the neutral axis, which section is then folded to lie in a plane transverse to that of the flange A with the edge 45 which was originally next to the edge a adjacent to said flange A and extending parallel thereto until the edge b is in close proximity to the flange B. The flange B also has a section D struck out in a similar manner 50 and folded to overlap the section C to which

it is rigidly secured by suitable means such as spot-welding or riveting. These two sections are, however, preferably struck out from unalined portions of the flanges A and B, extending upon opposite sides of the 55 plane of the folded sections so as to avoid weakening the member at any one point in its length. The sections are also preferably of greater length than width so as to be formed of metal that is out of work by reason of its proximity to the neutral axis and yet of sufficient extent to form the brace. In Figs. 1 to 4 inclusive, I have shown a beam which is formed in a similar manner, having adjacent web portions thereof cross-braced 60 and connected to each other in a similar manner. Fig. 1 represents the blank before folding, which comprises three portions E F G, folded upon the dotted lines H I J K L and M to form parallel webs of the portions 65 E and G, a cap of the portion F and return-bent flanges N of the portions between the dotted lines H J and K M. These three portions E F and G are then connected and 70 cross-braced by struck-out portions similar to those shown in Fig. 5. In detail, the portion E has a section O which is struck out from adjacent to the plane of the neutral axis and is of sufficient length so that when folded along the oblique line P it will extend 75 adjacent to the cap section F. The opposite edges of this section O lie adjacent to the portion E and the parallel web portion G, forming a brace therebetween. The web section G is provided with a similarly struck-out and folded portion Q, while the portion F has a section R struck out therefrom and bent downward. All of these struck-out sections lie in transverse parallel planes adjacent to each other, and they are rigidly secured by riveting, spot-welding, or in any other suitable manner as indicated at S. The apertures formed by the striking-out of 80 these sections are, however, alined with each other and those of the portions E and G lie 85 upon opposite sides of the plane of the folded brace, as shown.

If it is found expedient to strengthen the cap portion of the beam this may be accomplished by reinforcing members placed adja- 90 95 100

cent thereto as indicated by the dotted lines T, which sections may be riveted or spot-welded to the section F.

While I have shown the construction as formed from an integral blank, it is obvious that it might be formed from separate sections riveted, spot-welded, or otherwise secured to each other, and cross-braced in a similar manner.

10. What I claim as my invention is:

1. In a structural element, the combination with spaced web members, of a section struck out from the metal of one of said webs adjacent to the neutral axis thereof, 15 said section being folded inward between said webs to form a spacer and brace-member therefor.

2. In a structural element, the combination with spaced web members, of a section 20 struck out from the metal adjacent to the neutral axis of one of said web members of a width corresponding to the space between said webs, said section being bent inward in a plane transverse to the webs and folded 25 at an angle to extend with its opposite edges adjacent to said webs.

3. In a structural element, the combination of spaced web members, a section struck 30 out from the metal adjacent to the neutral axis of one of said web members, being of a width equal to the space between said web members and of a greater length, said section being bent inward into a plane transverse to the webs and folded at an angle to 35 extend with its opposite edges adjacent to said webs, and a flange struck out from the opposite web member extending parallel and secured to said section.

4. A structural element, comprising a 40 sheet metal blank folded to form a cap portion and parallel spaced web portions extending in planes transverse to the cap, one of said web members having a section thereof adjacent to the neutral axis partially severed and folded inward, said section being then folded at an angle to extend between said webs with its opposite edges adjacent thereto, and a struck-out section from the opposite web lying adjacent and secured to 50 said section.

5. A structural element, comprising a sheet metal blank folded to form a cap member and parallel web portions extending in planes transverse to the plane of the 55 cap, said webs having corresponding sections partially severed therefrom adjacent to the neutral axis and folded inward, said sections being of a width corresponding to the spacing between said webs, and each being folded at an angle to extend with its opposite edges adjacent to said webs, and a section struck downward from the metal of 60 said cap lying adjacent to said folded section and being secured thereto.

6. A structural element, comprising a 65 sheet metal blank folded to form a cap member and parallel web portions extending in planes transverse to the plane of the cap, unlined sections struck out from said web portions adjacent to the neutral axes thereof 70 folded inward to lie adjacent to each other and to extend between said webs, said sections being secured to each other to form a connecting brace, and means for attaching said brace to said cap section. 75

7. A structural element, comprising a sheet metal blank folded to form a cap member and parallel web portions in planes transverse to the plane of said cap, unlined sections struck inward from said web portions adjacent to the neutral axes thereof 80 and bent to lie in adjacent planes, the width of said sections corresponding to the space between said webs and being of a greater length and folded at an angle to have their 85 opposite edges lie adjacent to said webs, and their ends extending adjacent to said cap, and a section struck down from said cap lying adjacent to said sections from the webs and secured thereto. 90

8. In a structural element, the combination with a sheet metal web of a section struck out therefrom adjacent to the plane of the neutral axis thereof, folded upon itself and bent to lie in a transverse plane 95 with one edge parallel and adjacent to the original plane of the web, said section forming a cross-brace or connection with an adjacent member. 99

9. In a structural element, the combination with a web portion, of a section struck out from the metal lying adjacent to the plane of the neutral axis of said web, being of greater length than width, said section being folded upon itself to lie in a transverse 100 plane with one edge thereof extending parallel and adjacent to the original plane, and an adjacent web section having a struck-out portion overlapping said first-mentioned struck-out section and connected thereto. 100

10. In a structural element, a sheet metal web having a section struck out from the metal lying adjacent to the plane of the neutral axis thereof and of greater length than width, said section being folded upon 115 itself to lie in a transverse plane with one edge parallel and adjacent to the original plane and extending laterally from the aperture formed in the web by the removal of the section, and a flange bent from said web to lie in a plane at an angle thereto, said flange having a struck-out portion lying adjacent to said first-mentioned struck-out portion and secured thereto. 120

11. A structural element comprising a 125 sheet metal member bent to form a beam having web portions in transverse planes, a section struck out from one of said

web portions adjacent to the plane of the neutral axis thereof and folded upon itself to lie in a plane transverse to both of said web sections, one edge of said section lying adjacent to its original plane and one end thereof extending adjacent to the plane of the other web portion, and a section struck out from the last-mentioned web portion

lying adjacent to the first-mentioned struck-out portion and secured thereto. 10

In testimony whereof I affix my signature in presence of two witnesses.

CLIFFORD L. DUNBAR.
